UNITED STATES PATENT OFFICE.

CHRISTIAN HAVESTADT, OF WILMERSDORF, NEAR BERLIN, GERMANY.

DEVICE FOR EXHAUSTING AIR FROM SIPHONS OF SLUICES AND THE LIKE.

No. 902,077.

Specification of Letters Patent.

Patented Oct. 27, 1908.

Application filed May 24, 1907. Serial No. 375,478.

To all whom it may concern:

Be it known that I, CHRISTIAN HAVESTADT, of Wilmersdorf, a subject of the King of Prussia, and whose post-office address is No. 6 155 Berlinerstrasse, Wilmersdorf, near Berlin, Prussia, German Empire, have invented new and useful Improvements in Devices for Exhausting Air from Siphons of Sluices and the Like, of which the following is a 10 specification.

The invention relates to means for removing the air from siphons such as are used in sluices, water reservoirs and the like.

Hitherto stationary suction chambers or 15 movable suction bells have been employed for this purpose, the water contained therein being let off into the lower level of the sluice so as to obtain in the chamber or in the bell the necessary space for the air to be removed 20 from the siphon. These stationary suction chambers however have the disadvantage that a water column must remain between the air in the suction chamber and the atmosphere of a height equal to the difference 25 in pressure between the pressure in the chamber and the atmospheric pressure. It is therefore necessary to arrange the stationary suction chamber at as high a level as possible. Movable suction bells have therefore already been employed for exhausting 30 the air from siphons in sluices or locks, to obtain the space necessary for the air removed from the siphon. The mechanical means however employed for raising or lifting 35 such movable bells for the purpose aforesaid required power especially if the raising is to be effected quickly, the power increasing according to the increasing attenuation of the air.

According to the present invention a floating suction chamber is employed for exhausting the air from siphons of sluices, reservoirs and the like, *i. e.* a suction chamber which is provided with one or more outlet or discharge pipes and is connected up to the suction conduit of the siphon and the chamber not being stationary but rigidly connected with a floating chamber or casing so that it floats freely in the water, being 45 guided vertically in a similar manner to a gas collecting bell. This floating suction chamber has the advantage that it enables siphon locks to be used for sluices with considerably fluctuating falls such as sea sluices,

as the floating suction chamber adapts itself 55 to the various water levels which a stationary chamber is not capable of and it has the further advantage as compared with the mechanically raised suction bells, that it requires no special external power for raising 60 it.

The accompanying drawings illustrate two modes of carrying out the invention.

Figures 1 and 2 show in section and in 65 two different positions a simple form of suction chamber which is filled from the lower portion or level of the sluice by means of only one discharge pipe. Fig. 3 shows in section another form having two discharge or flow off pipes which may be closed if the 70 suction chamber is to be filled from the upper part of the sluice.

In carrying out the invention according 75 to one mode as illustrated by Figs. 1 and 2, the suction chamber, *a*, is rigidly connected with a closed floating chamber or casing, *b*, by means of a framework, *r*, or the like and is connected with deep water by means of one discharge pipe, *f*, although more than one may be used. Guide rails, *c*, are arranged on the supporting or side walls, *k*, the chamber, *a*, and the floating chamber or casing, *b*, being guided up and down thereon by means of rollers, *g*, in a similar manner to a gas collecting bell. *d*, is the suction 80 pipe leading to the sluice siphons. The vertical part of the pipe, *d*, works in an air tight stuffing box, *e*, leading to the suction chamber, *a*.

In the position shown in Fig. 2 the tank *a* 90 is filled, the pipe *d* is closed by means of a known suitable distributing device such as a three-way cock or the like (not shown in the drawings) against the atmosphere. Within the said pipe *d* in the said position 95 of the chamber *a* is a partial vacuum. Within the siphon is atmospheric pressure, so that when by means of the said distributing device the pipe *d* is opened for connecting the chamber *a* with the siphon, air passes 100 from the latter into the said chamber *a*, thereby displacing the water from the chamber through pipe *f*. The chamber *a* and the floating chamber *b* are raised corresponding 105 with such displacement of water until the chamber is completely emptied and reaches its highest position, as shown in Fig. 1. A water column stands in the discharge pipe *f*

balancing the partial vacuum in the chamber *a*.

Within the siphon the overflow of air into the chamber *a* effects a diminution of pressure of the remaining air. In consequence the atmospheric pressure lifts the water in both legs of the siphon. As soon as the water in the leg connected with the upper level or pond of the sluice has reached the ridge of the siphon and flows over into the other leg connected with the under level or pond of the sluice, the air yet contained in the siphon is taken away and the siphon is completely filled with running water. In consequence the air in the chamber *a* is sucked off through the pipe *d* and water enters from the under sluice level through the discharge-pipe *f* and fills the chamber *a*. Now the chamber *a* together with the floating chamber *b* sinks again. For the initial filling of the chamber *a*, a suitable air pump can be used for sucking off air from the pipe *d* and the chamber *a*. After the chamber *a* has been filled and a partial vacuum has been produced in said pipe *d*, the latter is closed against the atmosphere in the manner described. But preferably an arrangement is provided for making the initial filling from the upper level of the sluice, as shown in Fig. 3 of the drawings.

In the form of construction shown in Fig. 3 two discharge pipes, *f*, are provided which may be closed by means of valves, *h*, if the tank or chamber, *a*, is intended to be filled, from the upper level by means of a special filling connection, *i*, the chamber, *a*, being connected in this case with the upper part of the sluice by means of a flexible conduit such as a hose *j*, or the like provided with a corresponding connecting piece.

For the purpose of initial filling and producing a partial vacuum within the pipe *d*, the valves *h* are closed and the valve *i* of the hose *j* opened. Before the chamber *a* has been completely filled, the pipe *d* is closed against the atmosphere. Then the valve *i* is closed and the valves *h* are opened. Now the apparatus is in the condition as shown in Fig. 2 and its function is as referred to.

What I claim and desire to secure by Letters Patent of the United States, is:

1. In a device for exhausting air from siphons of sluices and the like the combination of a suction chamber, a floating chamber, means rigidly connecting the suction chamber with the floating chamber, a water discharge pipe on the suction chamber and means for movably connecting the suction chamber with the suction pipe leading to the siphon, substantially as set forth.

2. In a device for exhausting air from siphons of sluices and the like the combination of a suction chamber, a floating chamber, means rigidly connecting the suction chamber with the floating chamber, a water discharge pipe on the suction chamber, a valve for closing the discharge pipe, means for movably connecting the suction chamber with the floating chamber, a water

discharge pipe on the suction chamber, means for movably connecting the suction chamber with the suction pipe leading to the siphon and means for guiding the said chambers substantially as set forth. 70

3. In a device for exhausting air from siphons of sluices and the like the combination of a suction chamber, a floating chamber, a framework rigidly connecting the suction chamber with the floating chamber, a water discharge pipe on the suction chamber, 75 and means for movably connecting the suction chamber with the suction pipe leading to the siphon, substantially as set forth.

4. In a device for exhausting air from siphons of sluices and the like the combination of a suction chamber, a floating chamber, means rigidly connecting the suction chamber with the floating chamber, a water discharge pipe on the suction chamber and 80 a telescopic pipe for movably connecting the suction chamber with the suction pipe leading to the siphon, substantially as set forth.

5. In a device for exhausting air from siphons of sluices and the like, the combination of a suction chamber, a floating chamber, means rigidly connecting the suction chamber with the floating chamber, a water discharge pipe on the suction chamber, and 85 a telescopic pipe having connection with the suction chamber through an air-tight stuffing box, substantially as set forth. 90

6. In a device for exhausting air from siphons of sluices and the like the combination of a suction chamber, a floating chamber, 100 means rigidly connecting the suction chamber with the floating chamber, a water discharge pipe on the suction chamber, guide rails between which said chambers work up and down, rollers on said chambers working 105 on said rails, and means for movably connecting the suction chamber with the suction pipe leading to the siphon, substantially as set forth.

7. In a device for exhausting air from siphons of sluices and the like the combination of a suction chamber, a floating chamber, means rigidly connecting the suction chamber with the floating chamber, a water discharge pipe on the suction chamber, 110 means for closing the discharge pipe, means for movably connecting the suction chamber with the upper part of the sluice and means for movably connecting the suction chamber with the suction pipe leading to 115 the siphon, substantially as set forth.

8. In a device for exhausting air from siphons of sluices and the like the combination of a suction chamber, a floating chamber, means rigidly connecting the suction 120 chamber with the floating chamber, a water discharge pipe on the suction chamber, a valve for closing the discharge pipe, means for movably connecting the suction chamber with the upper part of the sluice and means 125

130

for movably connecting the suction chamber with the suction pipe leading to the siphon, substantially as set forth.

9. In a device for exhausting air from siphons of sluices and the like the combination of a suction chamber, a floating chamber, means rigidly connecting the suction chamber with the floating chamber, a water discharge pipe on the suction chamber, means for closing the discharge pipe, a flexible conduit for movably connecting the suc-

tion chamber with the upper part of the sluice and means for movably connecting the suction chamber with the suction pipe leading to the siphon, substantially as set forth. 15

In testimony whereof I have hereunto set my hand in presence of two subscribing witnesses.

CHRISTIAN HAVESTADT.
